A. TANNER.
HEMP AND FLAX MACHINE.

Patented Oct. 24, 1811.

Apparatus for
Breaking and
Stringing
Hemp & Flax

1597X

S. M. T. Patent

The Apparatus referred to in this S. M. T. Patent and, making part
of the same, constituting a continuation in the scope of the same, is
that I have invented of his Machine for Breaking and Stringing
Hemp & Flax.

This machine is to be put in motion by the force of
men or animals, wind, water or steam or common horses, may
render necessary or convenient, But as animal force may be most
conveniently applied, I shall proceed to describe the machine as deriving
its motion from that source. It has a central shaft, of any con-
venient diameter, turned by a horse or other animal. The shaft
shall communicate motion to another wheel or tramale head
on an upright slope which also carries a horizontal band
which shall give motion to the cutting wheel by hand or strap
or spring, or when no pulleys on the axis of the said cutting wheel
the cutting wheel is turned from the side, in the line of the said
The axis of this wheel lie in an inclined position so that the knives
incline from the vertical line which, instead of placing the said Spar-
-tular Claws as my invention! But the said may be placed
horizontally if the Constructor pleases. The cutting board or
wheel the strap or spring is held to be stringed is advanced to the
knives by a brace or trussle and withdrawn by a spring at the
option of the operator. A number of vertical prong pins rising
above the band wheel with friction rollers on them by striking
against a moving arm or lever by means of a pulley that ex-
-tracts from the lever to the moving jaw to break given motion to
the break by the revolution of the wheel. There may be any number of these
knives and cutting wheels moved by the same band wheel at the will of
the Constructor of the machine and if thought convenient claws may
be substituted for bands and cog or pin wheel to handle the board
